R. W. SCOTT.

WELTED KNIT STOCKING OR OTHER GARMENT AND ART OF KNITTING THE SAME.
APPLICATION FILED JULY 24, 1914.

1,125,190.

Patented Jan. 19, 1915.

UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

WELTED KNIT STOCKING OR OTHER GARMENT AND ART OF KNITTING THE SAME.

1,125,190.

Specification of Letters Patent.

Patented Jan. 19, 1915.

Application filed July 24, 1914. Serial No. 852,895.

To all whom it may concern:

Be it known that I, ROBERT W. SCOTT, a citizen of the United States, and resident of Boston, in the county of Suffolk and State of Massachusetts, have invented certain new and useful Improvements in Welted Knit Stockings or other Garments and Art of Knitting the Same, of which the following is a specification.

10 My invention relates to knit fabric having welts or hems and especially to plain knit articles having outturned welts and cuffs or tops of the general character illustrated in my Letters Patent 1,071,100, dated August 26, 1913.

One object of my invention is to provide an improved article of this class having a welt of a comparatively close texture attached to the remainder of the article in an improved manner.

Figure 1 is a side view of a stocking embodying my invention; Fig. 2 is a diagram plan of a row of needles illustrating the steps of manufacture on a machine; Fig. 3 is an enlarged outer or face view of the fabric showing the juncture of the welt and the top and the juncture of the top and the body of the article; Fig. 4 is a view similar to Fig. 3 showing a modified structure.

30 My improved article may be composed of flat or tubular fabric. In one instance, I may provide an integral welt W, and top T for a circular knit or seamless stocking such as shown in Fig. 1, having a leg L and a foot F, and a heel and toe of the usual form, the leg L consisting of fabric of any desired number (which may be that of all of the needles in a machine hereinafter termed a full number) of needle-wales in width, the 35 top T having therein fewer needle wales, and the welt W comprising a sufficient number of needle-wales to insure the desired texture. As illustrated, the latter number may be half the full number of needle-wales 40 in the leg L.

In the illustrative instance shown the top T is provided at every fourth wale a' with a dropped or missed stitch line caused by failure to knit in that wale, the yarns between 45 the needle-wales b on either side of the wale a' floating unknit, as shown at h. The fabric of the top thus comprises solid sections of adjacent wales a and b of plain knit fabric which may be two, three or more needle-wales in width. It will be understood that

the wale a' may occur in any order among the other wales. I prefer to begin the welt in the manner illustrated in Fig. 10 of my Letters Patent No. 1,079,267, dated November 18, 1913, by first feeding a yarn 1 to alternate needles, which may be the needles a and a' (for convenience given the same reference characters as the wales they knit) and by then feeding a second or following course to all of the needles, recurrent needles between the needles which take the yarn on the first course then retiring to hold their loops during knitting to form the fabric for the welt W on the needles a and a'. In the instance shown, the retired needles are the alternate needles for the wales b, and when they are retired, at the second course as shown, the said needles b withhold loops w.

As in my said Patent 1,079,267, upon completion of sufficient fabric knit in the wales a and a' only for both the inner and outer parts of the welt, as when the course 28 shown in the drawings has been formed, I join the last course of the welt to the body of the fabric by restoring to operation the needles holding the loops w to form a uniting course Z knit on the full number of needles, which course has loops y in the wales a penetrating all of the terminal loops of the welt fabric in the course 28 and loops z penetrating all of the loops w withheld from the course 2.

In order to make the top T of fabric having therein dropped or missed stitch lines, it is necessary to provide against running back or raveling only in those wales essential to holding the welt attached to the fabric of the top, which are the wales containing the loops w by which the face wall of the welt is attached, and a sufficient number of the wales of the back wall of the welt to preserve its continuity with the fabric of the top T. If the loops x in wales a of course 28 and all of the loops w are prevented from dropping, for instance, the loops x' need not be locked, since if released the only effect will be to make ladders or runs in the spaced wales a', extending as far as the fold at the top of the welt, beyond which, as I have determined by experiment, the loops will not run under any ordinary strain of use. That loop x' at the left of Fig. 3 is shown dropped in this manner. Such runs or ladders whether occurring in all of the wales a' or only in scat-

tered wales are damaging neither to the appearance nor the utility of the stocking, being confined to the concealed fabric of the inside or back wall of the welt.

Having provided standing wales *a* continuous through the welt and top, I may therefore freely drop off their needles, to form drop-stitch lines, such a number of loops in other running wales *a'* not occurring in the same wales as the loops *w* or the loops *x*, as will secure the desired fabric for the top *T*. I may drop the loops *x'* at course 28, or following the loop in course *Z*, but as illustrated in Fig. 3, I prefer to first form a section of fabric *S* of a few courses knit at the full number of needles and containing wales continuing all of the loops of the uniting course *Z*. The needles for the wales *a'* are then operated to drop their stitches.

Ladders or runs extending to the top fold of the welt in the wales *a'* may be formed as a step in the manufacture, or the fabric may be left in the condition illustrated at the right of Fig. 3. With yarns of some sorts ordinary strains will be insufficient to unlock the terminal knit loops in wales *a'*, the section *S* retaining all of its knit wales in use. When I refer to dropping the loops in the wales *a'*, it will be understood the needle *a'*, may be retired completely, after casting its loop, or said needle may be operated so as to take yarn and cast off at each course, without knitting. When sufficient fabric *T* is completed knitting in the wales *a'* is again resumed for the leg *L*, the heel, foot and toe. When it is desired to secure the fabric against running back at the drooped wales *a'*, for instance when it is desired as an element of design or appearance to provide an extent of full-number fabric *S* sufficient to make a prominent effect in the article, I may employ the structure shown in Fig. 4.

It will be noticed that the needles *b*, which are not employed in the welt, are necessarily capable of withholding their loops during knitting upon the remaining needles. Having formed the course *Z* and the succeeding courses such as 30 to 34, I now cause the needles *b* to withhold their loops as at *g* in said Fig. 4, while continuing to knit in the wale *a* and *a'* to form for instance the courses 35 and 36, the yarns of which will be cast off over the heads of the loop-retaining needles in the wales *b*, and pass behind said wales *b*, but will be knit by the needles *a* and *a'*. Having completed said courses I now operate the needles *a'* to cast off, whereupon they drop the terminal loops *w* in the wales *a'*. Knitting is now resumed on all the needles except those at *a'*, at course 37 for instance. The natural curl of the fabric will have thrown the terminal loop or pair of loops forward between the needles ad-

jacent to the needles upon which they were knit, and the yarn 34 of the succeeding course will pick up and hold the said loops *x* toward the face of the fabric, causing them to penetrate the sinker or float wale between the two needles *b* in either side of the needle *a'*. I have explained and claimed in my application Serial No. 823,121 another species of this structure, which forms an efficient frictional lock to prevent raveling of a dropped wale. In the present case, this effect is aided by loops *g* in the wales *b* taking the longitudinal strains, which can not be transmitted through the wale *a* because of the extra number of loops of course 35 and 36 in said wale.

The fabric for the top *T* may be knit of a yarn different from the welt *W* and the fabric *S*, as illustrated in solid black, and I prefer to retain this yarn in use at least through that course in which all of the needles are restored to action to knit the fabric *L* in order to permit the stiffness of the usually heavier yarn for the top *T* to aid in reducing the size of the eyelet hole formed in the wales *a'*.

In connection with Fig. 2 I have illustrated, merely to indicate capacity for differently operating the particular needles, short jacks *j'* for the needles *b*, longer jacks *j''* for the needles *a*, and still longer jacks *j'''* for the needles *a'*. The operations described when performed by machine require the needles *b* to be retired from action while holding their loops during knitting upon the remainder and require the needles *a'* to be capable of being operated so as to cast off and retire, or to cast off in each course, during normal knitting upon the remainder. These operations may readily be performed in an independent needle knitting machine by suitably operating the jacks of different lengths selectively at the required times.

What I claim is:

1. A knit garment having an integral welt in which there are wales of knit loops continuing into the adjacent part of the garment; some of said wales being standing wales continuous with solid knit adjacent fabric and some being wales terminating in dropped stitches.

2. In a knit fabric, an integral knit welt united at one end to the adjacent fabric and having certain wales continuous at the other end with the wales of said adjacent fabric, the intervening wales of said welt fabric terminating in stitches dropped in the adjacent fabric.

3. A knit garment having a top containing sections of solid fabric separated by wales of unknit yarn, said garment comprising an integral welt having standing knit wales corresponding to some of the wales of said solid fabric, and other knit wales corresponding to said wales of unknit yarn.

4. In a knit article, an out-turned welt comprising an initial course, a subsequent course having withheld uniting loops and continuous front and back walls formed of fabric whose knit wales stand between said withheld loops, the adjacent section of said article comprising sections each having wales in continuation of said withheld loops, and other wales in continuation of certain recurrent wales only of the welt fabric.
5. A stocking having a top of adjacent wales of solid plain knitting separated by wales of unknit yarn, said top being provided with an integral welt united at one end to initial stitches of some of the wales of solid plain knitting, some of the wales of the welt being continuous at the other end with some of the wales of solid plain knitting, the remaining wales of the welt terminating in dropped stitches corresponding to said wales of unknit yarn.
6. In a stocking, a top comprising sections of solid plain fabric and wales of unknit runs or floats of yarn, and a section longitudinally continuous therewith having therein one or more courses of yarn inter-

knit in one of the wales passing through each of said sections of solid plain fabric, one of said courses having a loop cast off in each of said unknit wales, the yarn of said courses passing behind other wales.

7. The art of knitting welted garments having a cuff or top of fabric having solid sections separated by lines of unknit yarn, on a series of instruments, comprising supplying yarn to all of said instruments, withholding loops at recurrent instruments distributed among the others, then knitting fabric for a welt at the remaining instruments, thereafter knitting a uniting course through said withheld loops and terminal loops of said welt fabric, and then dropping stitches at certain only of those instruments intervening between said recurrent instruments.

In testimony whereof, I have signed my name to this specification in the presence of two subscribing witnesses.

ROBERT W. SCOTT.
